UNITED STATES PATENT OFFICE.

ARCHIE BRYAN STRINE, OF QUANTICO, VIRGINIA.

FLYING MACHINE.

Application filed January 14, 1924. Serial No. 686,169.

To all whom it may concern:

Be it known that I, ARCHIE B. STRINE, a citizen of United States, residing at Quantico, in the county of Prince William and State of Virginia, have invented new and useful Improvements in Flying Machines, of which the following is a specification.

This invention relates to improvements in aircrafts, the general object of the invention being to provide large wings above and below the fuselage, which is of small dimensions, so as to increase the wing surface and render it possible for the plane to take off 15 in short distances and to land in a small field.

Another object of the invention is to so form the upper wing that the gasoline tank may be located therein.

This invention also consists in certain other features of construction and in the combination and arrangement of the several parts, to be hereinafter fully described, illustrated in the accompanying drawings 25 and specifically pointed out in the appended claim.

In describing my invention in detail, reference will be had to the accompanying drawings wherein like characters denote like 30 or corresponding parts throughout the several views, and in which:—

Figure 1 is a plan view of a plane constructed in accordance with this invention.

Figure 2 is a front view.

Figure 3 is a side view.

Figure 4 is a section on line 4—4 of Figure 2.

Figure 5 is a section on line 5—5 of Figure 3.

Figure 6 is a section on line 6—6 of Figure 3.

Figure 7 is a view of the gasoline tank.

In these views, 1 indicates the fuselage, 2 the landing gear, 3 the propeller, 4 the rudder, 5 the elevator, 6 the stabilizer and 8 the cables for moving the rudder and elevator from a point adjacent the pilot's seat in the fuselage.

In carrying out my invention I make the fuselage of small dimensions and place 50 above the same a large wing 9 and a smaller wing 10 is placed below the fuselage, these wings 9 and 10 having the side wings 11 connected with their sides, as shown. The upper wing 9 is made hollow and contains the 55 gasoline tank 12 which is connected by the pipes 13 with the motor in the fuselage. This wing is braced by the central piece 14 of wood or hollow steel tubing and the other braces 15. Braces 16 connect the rear parts 60 of the wings 9 and 10 together. The wings 9 and 10 are of the shape shown.

From the foregoing it will be seen that the wing surface of the plane is greatly enlarged and by making the wings 9 and 10 65 hollow their interiors may be used for carrying certain parts which are ordinarily carried in the fuselage so that the size of the fuselage can be decreased and thus doing away with the resistance of a large 70 fuselage in the passage of the plane through the air. A plane constructed in accordance with this invention permits the plane to be easily handled and it can take off and land in a comparatively small space. 75

It is thought from the foregoing description that the advantages and novel features of my invention will be readily apparent.

I desire it to be understood that I may make changes in the construction and in the 80 combination and arrangement of the several parts, provided that such changes fall within the scope of the appended claim.

What I claim is:—

An airplane comprising superposed 85 planes, a fuselage located between the planes, each of said planes comprising laterally projecting wing portions and a hollow central portion, forming a carrying compartment of greater depth and chord 90 than the said wing portions.

In testimony whereof I affix my signature.

ARCHIE BRYAN STRINE.
